The ornamental design for the glass pendant for decorative light fixtures, as shown and described.

DESCRIPTION

FIG. 1 is perspective view of the glass pendant for decorative light fixtures showing my new design;

FIG. 2 is a front elevation view of the glass pendant for the decorative light fixtures of FIG. 1;

FIG. 3 is a left side elevation view thereof;

FIG. 4 is a right side elevation view thereof;

FIG. 5 is a rear elevation view thereof;

FIG. 6 is a top plan view thereof; and,

FIG. 7 is a bottom plan view thereof.
